(57) **CLAIM**

The ornamental design for the light fixture, as shown and
described.

DESCRIPTION

FIG. 1 is a perspective view of the light fixture present
invention; and

FIG. 2 is a first side view of the present invention; and
FIG. 3 is a second side view of the present invention; and
FIG. 4 is a third side view of the present invention; and
FIG. 5 is a fourth side view of the present invention;
FIG. 6 is a top view of the present invention; and,
FIG. 7 is a bottom view of the present invention.

The broken lines shown on the drawings depict portions of
the light fixture that form no part of the claimed design.
